UNITED STATES PATENT OFFICE.

CHARLES C. RUSSELL, OF CHICAGO, ILLINOIS.

CAR-DOOR HANGER.

1,142,532.

Specification of Letters Patent.

Patented June 8, 1915.

Application filed April 26, 1915. Serial No. 24,037.

To all whom it may concern:

Be it known that I, CHARLES C. RUSSELL, a citizen of the United States, and resident of Chicago, county of Cook, and State of Illinois, have invented certain new and useful Improvements in Car-Door Hangers, of which the following is a specification, and which are illustrated in the accompanying drawings, forming a part thereof.

The invention relates to the doors of railway freight cars and more particularly to the means employed for supporting and guiding the door in its edgewise movement over the door opening.

The object of the invention is to provide an improved car door hanger construction which shall be efficient in operation, embodying the use of only inexpensive materials and parts and serve the additional function of strengthening the car door.

In the accompanying drawings, Figure 1 is a detail side elevation of a railway box car showing the door in open position. Fig. 2 is a transverse vertical sectional view of the same with some of the parts shown in elevation, and with other parts broken away. Fig. 3 is a detail sectional view showing one method which may be employed for securing the supporting and strengthening rail upon the door. Fig. 4 is a detail perspective view showing another form of attaching means employed for securing the said rail upon the door, and Fig. 5 is a detail longitudinal sectional view of an end portion of the rail, a terminal cap or head therefor being shown in elevation.

The side wall of a car is indicated at 10, its door opening being represented at 11. The door 12 has the usual edgewise movement over the side wall 10 of the car and in front of the opening 11. Outward movement of the lower edge of the door is prevented in any convenient manner as by means of guide brackets, one of which is conventionally shown at 13.

In carrying out the invention the door 12 is preferably constructed with a horizontal rabbet or recessed portion 14, extending along the upper edge of the door upon the inside. In the arrangement shown this rabbeted portion is provided by constructing the door 12 in two layers 15, 16, with the inner layer 16 terminating below the upper edge of the door. Within the rabbet 14, and against the exposed portion of the inside face of the outer layer 15, is secured an S-

shaped track, generally designated 17. This track is desirably constructed from a single piece of pipe bent to provide three horizontal rail sections 18, 19, 20, each substantially equal in length to the width of the door and with the adjacent sections connecting near the opposite margins of the door, as at 21, 22. This track is firmly secured in position and serves both as a guiding rail for supporting the door in its movement and as a reinforcement for stiffening the door.

The means employed for securing the track 17 in position upon the door will preferably be such as to firmly hold it against dislodgment. As shown, the pipe from which the track is formed is bored at intervals throughout its length to provide apertures 23 for the reception of attaching screws 24, or bolts 41 and openings 25, in alignment with each of the apertures 23, to permit the insertion of the attaching screws 24, or bolts 41, as also of tools to be used in setting the screws or bolts. Preferably the screws 23 are used at frequent intervals throughout the intermediate length of the track 17 and a bolt 41 which passes entirely through the outer layer 15 of the door is used adjacent each of the extreme ends of the track.

When the door 12 is positioned for service, the track 17 is engaged with rollers, as 29, 30, 31, 32, 33 and 34, arranged in two sets upon the side wall 10 of the car. The rollers of one set, as 29, 30 and 31 are located above the level of the top of the door opening 11 and are positioned to be embraced between the upper rail 18 and intermediate rail 19 of the track 17 in the closed position of the door. The rollers of the other set, as 32, 33 and 34 are located at one side of the door opening 11 and at the proper level to be embraced between the lower rail 20 and intermediate rail 19 of the track 17 in the open position of the door. Each of the rollers is rotatably mounted upon a bolt, as 35, which extends through the side wall 10 of the car, and preferably with a spacing washer 36 located under the roller. For the purpose of economizing space, the head, as 37, of each bolt 35, is countersunk in the outer face of the corresponding roller. To insure that the bolts 35 shall be held against turning with the rollers, as 29, mounted thereon, each of said bolts is preferably constructed with a lag screw thread 42 formed thereon, intermediate its ends for engage-

ment with the side wall of the car through which the bolt is extended.

When the track 17 is constructed from pipe as shown, each of the rollers 29, 30, 31, 5 32, 33 and 34 is formed with a grooved periphery and the greatest diameter of each roller is slightly in excess of the distance between the adjacent rails 18, 19 and 19, 20, of the track. The rollers accordingly serve 10 both for guidedly supporting the door in its edgewise movement and for preventing outward displacement of the upper portion of the door. If the rollers of the two sets be positioned for the engagement of the two 15 outer rollers as 29 and 31 of the upper set with the upper and intermediate rails 18, 19, of the track 17 adjacent their opposite ends, in the closed position of the door, and for the engagement of the outer rollers, as 20 32, 34 of the lower set with the intermediate and lower rails 19, 20 of the track 17 adjacent their opposite ends in the open position of the door, the track 17 will always be engaged with a sufficient number of the rollers 25 to efficiently support the door in any position. To facilitate the engagement of the rollers with the track in the movement of the door, the opposite ends of the track are preferably pointed, as by inserting a pointed plug in each end of the pipe from which the track is formed. The application of the door to the car is permitted if provision is 30 made for securing at least one of the rollers, as 31, in place upon the side wall 10 of the car after the positioning of the door. For this purpose the door 12 is formed with an opening 39 in line with the axis of the roller 32 in the open position of the door through 35 which the bolt 35 upon which the roller 32 is to be mounted and a tool for driving the bolt may be inserted. After the roller 32 has been fixed in position, the opening 39 is desirably closed by a plug 40. The track 17 is shown as being covered by a cleat 41^a 40 which is mounted upon the top of the outer layer 15 of the door and extends inwardly over the rabbet or the recessed portion 14 of the door.

I claim as my invention,—

1. In combination, a car wall having a 50 door opening therein, a door movable edgewise over the opening, two sets of peripherally grooved rollers mounted on the car wall, the rollers of each set being in horizontal alinement and the rollers of one set being 55 located above and extending over the door opening, the rollers of the other set being located at a lower level and at one side of the door opening, and a continuous track of round cross section secured against the 60 inside face of the door and folded to provide three rail lengths at different levels, the lower rail being engageable with the peripheral grooves of the rollers of the lower set from below, the upper rail being 65 engageable with the peripheral grooves of the rollers of the upper set from above, and the intermediate rail being engageable with the peripheral grooves of the rollers of both sets. 70

2. In combination, a car wall having a door opening therein, two sets of peripherally grooved rollers mounted on the car wall, the rollers of each set being in horizontal alinement and the rollers of one set being 75 located above and extending over the door opening, the rollers of the other set being located at a lower level and at one side of the door opening, a door movable edgewise over the door opening and being rabbeted 80 upon the inside along its upper edge, the depth of the rabbet being substantially equal to the thickness of the said rollers, and a continuous track secured against the bottom of the rabbeted portion of the door and 85 folded to provide three rail lengths at different levels, the lower rail being engageable with the peripheral grooves of the rollers of the lower set from below, the upper rail being engageable with the peripheral grooves 90 of the rollers of the upper set from above, and the intermediate rail being engageable with the peripheral grooves of the rollers of both sets. 95

CHARLES C. RUSSELL.
